GARMENT HANGER

Herbert L. Stell, Cleveland, Ohio

Application August 1, 1936, Serial No. 93,843

6 Claims. (Cl. 223—93)

This invention relates to garment hangers.

An object of the invention is to provide an improved garment hanger which may be used for a plurality of different types of garments.

5 Another object is to provide an improved garment hanger which will effectively hold garments from sliding off the hanger.

Another object is to provide an improved garment hanger in which the holding means may be concealed within the hanger when not in use.

Another object is to provide an improved garment hanger which will be simple in construction and operation.

15 Another object is to provide an improved garment hanger which will be neat and attractive in appearance.

Another object is to provide an improved garment hanger which may be economically manufactured.

20 Another object is to provide an improved garment hanger which may be effectively and simply secured to a support.

Other objects will hereinafter appear.

The invention will be better understood from 25 the description of two practical embodiments thereof, illustrated in the accompanying drawing, in which;

Figure 1 is a side elevational view, parts being broken away and shown in section, of one form of 30 hanger embodying the invention, showing the garment holding parts in concealed or retracted position;

Figure 2 is a view similar to Figure 1 of the same apparatus but showing the garment holding parts in operative or extended position; and

35 Figure 3 is a perspective view, parts being broken away and shown in section, of a modified type of hanger with the garment holding parts in extended position.

40 The hanger shown in Figures 1 and 2 consists of a supporting bar or frame composed of side plates 1 and 2 connected at their ends by blocks 3. These blocks are recessed at their inner upper corners, as indicated at 4, for the reception of the garment holding mechanism when in retracted or 45 folded position.

This mechanism consists of two somewhat resilient arms 5, conveniently of sheet metal or similar material, each terminating in a rectangular end 6, which, in folded position, fits within the recess 4, and in extended position bears upon the upper surface of block 3, clamping between these ends and the blocks the garment which it is desired to hold.

50 The arms have depending slotted lugs 7, which

slide over pins 8 spanning the space between the plates 1 and 2, and the ends of the arms terminate in loops surrounding pivots 9 by which the arms are connected to links 10, the lower ends of which are pivoted by pins 11 to a bar 12 secured as by rivet 13 to the lower end of a shank 14. The shank is guided in its upward and downward motion by slots 1a in the side plates, the ends of rivet 13 projecting into these slots and sliding therein as the shank moves up and down with respect to the arms. The upper end of this shank is formed into a hook 15 adapted to be placed over a supporting hook or rod.

This hook is arcuate in shape and formed into a channel-shaped cross section. Within the channelled part a guard or keeper consisting of an arcuate piece 16, provided with a looped handle 17, may slide from the position indicated in solid lines in Figure 1 to that shown in dotted lines therein, to secure the hook upon its supporting rod.

The operation of the device is as follows:

When it is desired to use the hanger in the conventional manner, as for hanging up a coat or similar garment, the holding mechanism is 25 concealed between plates 1 and 2 and blocks 3. This is done by pressing the shank 14 downwardly, which draws links 10 close together into substantially the position shown in Figure 1, when the ends 6 may be pressed into recesses 4.

30 The weight of the garment, tending to pull parts of the frame downwardly with respect to the shank 14, causes links 10 and arms 5, through their toggle-like action, to tend to extend the arms. Such extending, however, is prevented by abutting of the ends 6 against blocks 3, so that the links and arms are maintained under compression within the frame of the hanger.

35 When, however, it is desired to support a garment which may tend to slip off the hanger, such for instance as a dress having only straps to pass over shoulders, the holding mechanism is extended as shown in Figure 2 by pressing shank 14 downwardly until the ends 6 are only loosely in contact with the blocks and can be lifted therefrom.

40 The straps or other parts of the garment to be held are inserted between the ends 6 and blocks 3, and the weight of the garment, pulling 45 the frame downwardly relative the shank 14, causes the arms 5 to act as levers pressing their ends 6 upon the garment and through it upon blocks 3.

The hanger of Figure 3 is quite similar to that 55

of the first two figures, excepting that slotted lugs 7 have been replaced by pivoted links.

The frame consists of side plates 101 and 102, between which are interposed blocks 103, these being shown as extending nearly to the middle of the frame. Arms 105 are pivoted to links 107, the lower ends of which are pivoted upon pins 108 extending across the frame.

Links 110 connect the arms to a bar 112 carried by the lower end of shank 114, in substantially the same manner as in the embodiment above described.

Pins 118 limit the motion of links 107, while pins 119 assist slots 101a in guiding the shank.

15 The ends 106 of the arms 105 are provided on their lower surfaces with pieces of felt 106a to distribute pressure on the garment clamped between them and the blocks 103. The blocks 103 are also shown as provided with adjustable set 20 screws 103a which may be moved inwardly or outwardly to adjust for any variation in the position of the blocks or in the length of the arms.

25 While I have described the illustrated embodiments of my invention in some particularity, obviously many others will readily occur to those skilled in this art, and I do not therefore limit myself to the precise details shown and described, but claim as my invention all embodiments, variations and modifications coming within the scope of the appended claims.

I claim:

1. A clothes hanger comprising a frame, a pair of garment engaging arms movably carried thereby, the frame being formed to provide arm receiving recesses, the arms being movable from a position in the recesses of the frame to a position thereabove.

2. A clothes hanger comprising a frame, a pair of garment engaging arms movably carried thereby, the frame being formed to provide arm receiving recesses, the arms being movable from

a position in the recesses of the frame to a position thereabove, and means causing the arms to bear upon the frame.

3. A clothes hanger comprising a frame, a pair of garment engaging arms movably carried thereby, the frame being formed to provide arm receiving recesses, the arms being movable from a position in the recesses of the frame to a position thereabove, and means causing the arms to bear upon the frame, said means comprising a supporting member movable relative the frame, and connections between said supporting member and said arms.

4. A hanger comprising a hollow frame, a supporting member movable relative thereto, a pair 15 of resilient arms movable into and out of the hollow of the frame, pivotal connections between said arms and the frame, and pivotal connections between said arms and said supporting means.

5. A hanger comprising a hollow frame, a supporting member movable relative thereto, a pair of resilient arms movable into and out of the hollow of the frame, pivotal connections between an intermediate part of said arms and the frame, and pivotal connections between one 25 end of each of said arms and said supporting means.

6. A hanger comprising a frame consisting of two parallel side plates, blocks between the ends thereof, the blocks spacing the side plates apart to define upwardly opening arm receiving recesses within the frame, a supporting hook having a shank extending within said frame, links pivotally connected to said shank, two arms each having an end pivotally connected to one of said links, pivotal connections between the intermediate part of each arm and said frame within said recesses, said links and connections being so arranged that as the arms move upwardly out of the frame they move away from each other.

HERBERT L. STELL.
